UNITED STATES PATENT OFFICE.

RALPH K. SNOW AND ALBA B. PERDUE, OF LOS ANGELES, CALIFORNIA.

MOVING-PICTURE APPARATUS.

1,231,958.

Specification of Letters Patent.

Patented July 3, 1917.

Application filed November 21, 1916. Serial No. 132,510.

To all whom it may concern:

Be it known that we, RALPH K. SNOW and ALBA B. PERDUE, both citizens of the United States, residing at Los Angeles, in the county of Los Angeles and State of California, have invented new and useful Improvements in Moving-Picture Apparatus, of which the following is a specification.

10 This invention relates to a moving picture apparatus, and pertains especially to an apparatus for producing animated pictures by the use of opaque sheets upon which the pictures are printed.

15 It is an object of this invention to provide an apparatus which may be used either for observing pictures through an eye-piece by the aid of daylight, or for projecting the pictures.

20 It is another object to provide an apparatus suitable for using pictures printed on opaque sheets. The sheets may be printed and suitable for distribution with newspapers as advertising sheets or sold separately.

25 The form and size of the sheets are immaterial to our invention.

It is a further object of this invention to provide a mandrel for carrying the pictures which is so arranged as to properly display 30 pictures in an up-right position, the pictures being printed on the sheet at an angle to the edges.

We accomplish these objects by means of the embodiment of our invention illustrated 35 in the accompanying drawing, in which:

Figure 1 is a perspective view of our moving picture apparatus, a portion thereof being broken away to show the interior.

Fig. 2 is a vertical section through the 40 mechanism compartment.

Fig. 3 is one form of sheet suitable for use with the apparatus, and

Fig. 4 is another form of sheet suitable for use with the apparatus.

45 A casing 5 is provided which has partition walls 6 and 7 dividing the casing into three compartments. The middle compartment houses the mechanism for moving the pictures. The compartment at one end is 50 a projecting compartment, and the compartment at the other end is a viewing compartment. The wall 7 is provided with an open-

ing 8 for displaying a single picture at a time and wall 6 is provided with an opening 9 for simultaneously displaying a single 55 picture at a time.

Disposed in the mechanism compartment is a threaded shaft 10. Shaft 10 is canted with respect to the compartment and is secured to the walls of the casing, being held 60 against rotation. Mounted upon shaft 10 is a mandrel 11. Mandrel 11 is of such diameter that it is substantially tangent to the walls 6 and 7 at the openings 8 and 9. Upon rotation of the mandrel the latter is moved 65 longitudinally of the shaft 10 by reason of the threaded engagement therewith. Freely mounted upon the shaft 10 for rotation is a friction disk 12. Extending from the friction disk and secured thereto are bars 13 and 14. Bars 13 and 14 pass through openings in the mandrel so that the mandrel may slide upon the bars, but will be compelled to rotate with the bars and the disk 12.

Engaged with the friction disk 12 is a 75 friction wheel 15. Friction wheel 15 is mounted for rotation upon a tubular shaft 16 and is journaled in a bearing 17. Splined to shaft 16 is a clutch 18 arranged to clutch the friction wheel 15 to the shaft. Extending through tubular shaft 16 and mounted for rotation therein is a driving shaft 19. Secured to driving shaft 19 is a Geneva stop motion 20 which rotates shaft 16. Upon the other end of shaft 19 is mounted a sprocket 80 wheel 20 which is free to rotate upon the shaft. Splined to shaft 19 is a clutch 21 for engaging sprocket wheel 20 with shaft 19. Adjacent the upper wall of the casing is a line shaft 22 provided with a sprocket wheel 90 23 aligned with sprocket wheel 20. A sprocket chain 24 is passed over sprocket wheels 20 and 23. Fixed to line shaft 22 is a friction pinion 25 which is engaged with the friction disk 12. A handle 26 is provided on the shaft 19 for manual rotation thereof.

Pivottally secured to brackets on the casing are shifter rods 27 and 28. Shifter rod 27 is secured to clutch 21, and shifter rod 28 to clutch 18. Securing the ends of the shifter rods to each other, is a bar 29. Clutches 18 and 21 are so spaced by the bar 29 that when one clutch is in engagement

with its corresponding wheel, the other is disengaged from its corresponding wheel. Fingers 30 and 31 are formed on the bar 29 and extend into the longitudinal path of 5 the mandrel 11 so that when the mandrel reaches the end of its longitudinal travel it will engage a finger and move the clutches to throw the wheel which is rotating the mandrel out of operation and engage the 10 other wheel with the shaft, thereby returning the mandrel.

Shaft 10 is canted in order to provide for the use of sheets of pictures which may be conveniently printed. The sheets of pictures when disposed upon the mandrel to embrace the same will form a series of pictures in helical form. If a strip of a moving picture film is cut into lengths to accommodate the same to the length of a sheet and 20 the same printed upon the sheet with one end of a strip at the bottom of the sheet and the contiguous end of the next strip at the top, the sheet when formed into a cylinder would form a continuous helix of pictures. The pictures if printed and cut in this way would not be displayed upright through the openings 8 and 9 if the shaft 10 was horizontal. For this reason we have canted the shaft to brace the pictures in 30 an upright position. The strips of pictures may be printed on a rectangular sheet or they may be printed upon a sheet of the form shown in Fig. 4. The angle with respect to the horizontal in which the shaft 35 is disposed will vary with the size of the sheet and the particular form of sheet.

Pictures are progressively displayed before openings 8 and 9. Light is admitted through the top of the viewing compartment 40 in any suitable manner illuminating the pictures so that they may be viewed through the eye-piece. In the projecting compartment there is means for projecting light upon the picture from which it is reflected 45 through the projecting lens. This last mentioned means, not shown, may be of any construction, several of which are well known in the art,—reflecting mirrors and lights at the forward end of the compartment adjacent 50 the projecting lens.

What we claim is:

1. In a moving picture apparatus, the combination of a casing; partition walls in said casing dividing the latter into a viewing compartment, a mechanism compartment, and a projecting compartment, said partition walls provided with openings for the display of pictures, and an opening in said viewing compartment to admit light; 55 an eye opening in a wall of said viewing compartment for observing pictures; a mandrel in said mechanism compartment for carrying chronopictures, said mandrel disposed to display a picture before each of 60 said openings; operating mechanism for

moving said mandrel to successively and intermittently dispose pictures before said openings; a projecting lens in the wall of said projecting compartment; and means in said projecting compartment to project 70 light upon a picture, and reflect the same through said projecting lens.

2. In a moving picture apparatus, the combination of a casing; a partition wall in said casing provided with an opening for 75 the display of a picture; a threaded shaft; a mandrel for carrying chronopictures mounted on said shaft; mechanism to intermittently rotate said mandrel in one direction; mechanism to rotate said mandrel in 80 the opposite direction; and means operated by the longitudinal movement of said mandrel at the end of its travel to unclutch the mechanism rotating it and clutch the mechanism for rotating it in the opposite direction. 85

3. In a moving picture apparatus, the combination of a casing; a partition wall in said casing provided with an opening for the display of a picture; a threaded shaft; a mandrel for carrying chronopictures mounted on said shaft; a driving shaft; gearing for intermittently driving said mandrel in one direction from said shaft; gearing for driving said mandrel in the opposite direction from said driving shaft; double clutch means for engaging either gearing with said driving shaft and disengaging the other set of gearing; said clutch means disposed in the path of longitudinal 90 travel of said mandrel for actuation thereof at the ends of travel of said mandrel. 95

4. In a moving picture apparatus, the combination of a casing; a partition wall in said casing provided with an opening for 105 the display of pictures; a threaded shaft; a mandrel for carrying chronopictures mounted on said shaft; a driving shaft; a wheel freely mounted on said shaft; gearing connecting said wheel and mandrel to 110 rotate the latter in one direction; a clutch secured to said shaft and disposed to engage said wheel; a second driving shaft; a wheel freely mounted on said second shaft for rotating said mandrel in the opposite direction; gearing connecting the first named driving shaft and the second driving shaft for intermittently rotating the latter; a clutch secured to said second named driving shaft and disposed to engage said second wheel; and means securing said 115 clutches together so that when one is in mesh with its corresponding wheel the other is out of mesh, said means provided with fingers disposed in the longitudinal path of travel of said mandrel. 120

5. In a moving picture apparatus, the combination of a casing; a partition wall in said casing provided with an opening for the display of a picture; a threaded shaft 130

canted with respect to said casing; a mandrel for carrying chronopictures mounted on said shaft; mechanism to intermittently rotate said mandrel in one direction; mechanism to rotate said mandrel in the opposite direction; and means operated by the longitudinal movement of said mandrel at the ends of its travel to unclutch the mech-

anism rotating it and clutch the mechanism for rotating it in the opposite direction. 10

In witness that we claim the foregoing we have hereunto subscribed our names this 6th day of November, 1916.
